MOUNTING OF GYMNASTIC EQUIPMENT

Austin S. Moyer, Rte. 3, Box 212, Dundee, Oreg.

Filed Mar. 6, 1958, Ser. No. 719,681

2 Claims. (Cl. 272—60)

The present invention relates to improvements in gymnastic equipment mountings, and particularly for use with both indoor and outdoor gymnastic equipment.

The primary object of the invention is to provide gymnastic equipment mounting including a universal base support having supporting standards mounted thereon adapted to be used in connection with practically every form of gymnastic and playground equipment.

Another object of this invention is to provide a supporting base that can be placed on a level surface, such as the floors of gymnasiums, basements, or the like, using the usual mats on top of the same, and in the case of outdoor structures the base is countersunk into the ground surface employing a sawdust covering or the like for padding.

A still further object of the invention is to provide in a mounting structure of the class described above adjustable supporting standards that can be readily adjusted for supporting all forms of equipment.

Another object of this invention is to provide a supporting base and supporting standards that can be adjusted as to height and equipment to be used from childhood through adult life for continuous physical development programs.

And a still further object of this invention is to provide mounting means attaching to a base gymnastic equipment for the developing and exercising of all parts of the body. Heretofore, the various gymnastic equipment had to have very heavy individual expensive supporting bases, but with this invention one base is adapted to all types of equipment, thereby eliminating considerable cost and expense to the user.

Another object of this invention is to provide a complete set of gymnastic equipment which can be easily dismantled and stored in a minimum amount of space.

Other objects and advantages will become apparent in the following specification when considered in the light of the attached drawings, in which:

Figure 1 is a perspective view of the invention with parts broken away for convenience of illustration.

Figure 2 is a fragmentary elevational detail view of the upper ends of the standards.

Figure 3 is a perspective view of the invention illustrating its use with gymnastic equipment on a lower level, partially broken away for convenience of illustration.

Figure 4 is an enlarged fragmentary sectional view of the invention, taken on the line 4—4 of Figure 3, looking in the direction of the arrows.

Figure 5 is an enlarged fragmentary sectional view, taken on the line 5—5 of Figure 4, looking in the direction of the arrows.

Figure 6 is a side elevation of the invention which illustrates the base and standards supporting what is known as a horse.

Figure 7 is a side elevation of the invention which illustrates the base and standards supporting a buck.

Figure 8 is a side elevation of the invention which illus-

2

trates the base and standards supporting a trampoline.

Figure 9 is a perspective view of a teeter board mounted on the upper end of the standards.

Figure 10 is a front elevation of the invention which 5 illustrates a backboard for basket balls mounted upon the standards and shown in raised position.

Figure 11 is a perspective view of an attachment associated with the upper ends of the standards.

Figure 12 is a perspective view of another attachment 10 to the upper ends of the standards used for special exercising.

Figure 13 is an end view of the buck shown in Figure 7, partially broken away illustrating the construction of the same.

Figure 14 is a plan view of an alternate form of base, illustrating how the same can be separated for transportation or storage.

Referring now to the drawings in detail wherein like reference numerals indicate like parts throughout the 20 several figures, the reference character M indicates generally a mounting for gymnastic equipment constructed in accordance with the invention.

The gymnastic equipment mounting M includes a base B made of resin pressed plywood or other sheet material. Mounted adjustably on the base B are upwardly extending identical standards S. The standards S each include a vertical hollow supporting leg 14. The leg 14 is supported in its vertically extending position by a pair of braces 15. The lower ends of the leg 14 and braces 15 operate within spaced parallel slots 16 formed in the base B.

As seen in Figures 4 and 5, the lower ends of the leg 14 and braces 15 have flanges 17 associated therewith and arranged to bear against the lower surface of 35 the base B, preventing the standard S from being pulled upwardly through the slot 16. The flanges 17 are provided with internally and externally threaded sockets 18 which are threaded onto the lower ends of the leg 14 and the braces 15. Washers 19 are engaged over the sockets 18 and a nut 20 is then tightened thereagainst gripping the edges of the slots 16 between the flange 17 and the washers 19. A lock nut 21 threaded on the leg 14 and braces 15 is then brought into action, locking the whole assembly tightly in position.

40 When the device is to be used for supporting high gymnastic equipment, vertical extension supporting members 22 are telescoped within the upper ends of the legs 14 and held in vertically adjusted position by a pin 23, passing through an opening in the leg 14 and one of 45 the openings 24 formed in the member 22. The height of the members 22 can be somewhat adjusted by the location selected for passing the pin 23 through the same. Special fittings 25 are vertically slidably mounted on the members 22 and are held in place at the desired 50 elevation by fastening pins 26 which pass through a selected one of the openings 24 located in the members 22.

When the device is used as in Figure 1, the horizontal bars 27 pass through fittings 25 and are locked in 55 fixed position by set screws 28. Eye bolts 29 are threaded into a fitting 30 located on the upper end of the member 22 to receive hooks 31 of guy wires 32, bracing the vertical members 22. Guy wires 33 secure the vertical members horizontally. The lower end of the guy wires 32 are anchored by turnbuckles 34, as illustrated 60 in Figure 1.

Again referring to Figure 1, a trapeze 35 is supported by the horizontal bar 27. Rings 36 as well as a swing 37 are illustrated in broken lines, showing their attachment to the horizontal bar 27.

70 A low or high vault bar 38, indicated by broken lines, may also be mounted on the members 22 upon verti-

cally adjustable supporting brackets 39. Mats 40 are placed on top of the base B. The mats 40 are provided in the form of strips or sections so that as the supporting standards S are moved closer or further apart, they can be rearranged as illustrated in Figures 1 and 3.

Referring now to Figure 3, the mounting M is shown used for supporting gymnastic equipment on a lower level with the supporting legs 14 relatively close together. The vertical members 22 have been removed and the standards S are brought closer together so that horizontal bars 41 will be properly spaced. The horizontal bars 41 have legs 42 telescoped in the upper ends of the legs 14 of the standards S and locked therein by the pins 23.

Referring to Figure 6, I illustrate a horse 43 having downwardly extending legs 44 telescoped into the legs 14 and secured therein by the cross pin 23. The standards S are illustrated adjusted horizontally to an intermediate position between that shown in Figures 1 and 3, demonstrating that virtually any type of equipment can be mounted upon the base B.

Referring to Figure 7, I illustrate a buck 45 supported upon legs 46 telescoped within the upper ends of the supporting legs 14 of the standards S. In this case the standards S are brought relatively close together.

Referring to Figure 8, a trampoline 37 is shown mounted upon all four standards S on its individual supporting legs 48.

Referring to Figure 11, special supporting members 49 are telescoped into the supporting legs 14, adjusted for any desired elevation and locked in place by the pin 23. The upper ends of the members 49 are bent at right angles in the form of bars 50 for use as hand grips for performing various types of gymnastics. Referring to Figure 12, the bars 50 are shown turned to face one another supporting a chinning bar 51.

Referring to Figure 9, I illustrate a teeter board 52 mounted on the upper ends of the standards S by a special supporting bar 53 telescoped into the legs 14.

Referring to Figure 10, I illustrate a basket ball back-board assembly 54 mounted upon the upper ends of supporting members 55, which in turn are supported by telescopic mounting in the legs 14.

While I have illustrated just a few gymnastic pieces of equipment, there is no limit as to the number of different devices that can be adapted to this type of base mounting M.

Referring to Figure 4, I have illustrated the base B lowered into a pit 56 when used out-of-doors. A protective layer of material 57 is positioned beneath the base B to prevent moisture from entering the base B. Special cover plates 58 may also be added to the lower surface of the base for covering the bottom of the slots 16

so that dirt or other foreign matter cannot work up through the same.

The pit 56 is filled to the point 59 with sawdust or shavings, providing protection for the user of the equipment.

In the operation of this new and improved mounting M for gymnastic equipment, when the pieces of equipment to be used are selected, the lock nut 21 and the nuts 20 are loosened and the standards S moved to the desired position in regards to the space to accommodate the particular equipment being used, and then the nuts are again locked in place holding the standards S in a fixed position.

Having thus described the preferred embodiments of the invention, it should be understood that numerous structural modifications and adaptations may be resorted to without departing from the scope of the appended claims:

What is claimed is:

1. A gymnastic equipment support comprising a generally flat rectangular horizontal base, said base having three transversely extending spaced apart parallel slots formed therein adjacent each corner thereof, a standard assembly positioned in upright relation adjacent each corner of said base, a pair of outwardly and downwardly sloping braces having their upper inner ends rigidly secured to said standard assembly, and means on the lower end of said standard assembly and on the lower end of each of said braces releasably securing said assembly and said braces in transversely adjusted position in said slots, said standard assembly and said braces having the lower ends thereof extending into said slots and having means thereon for clamping said braces and said standard assembly to said base, said last mentioned means comprising a flanged sleeve threadably engaged on the lower end of each of said braces and said standard assembly with said flange engaging under said base and the sleeve extending through said slot and a clamping nut engaging over said base in clamping cooperation with each of said flanges.

2. A device as claimed in claim 1 wherein each of said standard assemblies is provided with means for supporting a gymnastic equipment leg telescopically mounted in said standard assembly.
